UNITED STATES PATENT OFFICE.

JAMES A. NORDEN, OF SOUTH VANCOUVER, BRITISH COLUMBIA, CANADA.

CULINARY ARTICLE.

1,283,272.

Specification of Letters Patent. Patented Oct. 29, 1918.

Application filed January 28, 1916. Serial No. 74,843.

To all whom it may concern:

Be it known that I, JAMES A. NORDEN, a subject of the King of Great Britain, residing at South Vancouver, in the Province 5 of British Columbia and Dominion of Canada, have invented certain new and useful Improvements in Culinary Articles, of which the following is a specification.

The present invention relates to culinary 10 articles and as its general object, it contemplates the provision of a novel device of this nature that is especially designed for cleaning and scraping the inner walls of pots, pans and other cooking utensils, and which 15 by reason of its novel construction, may be easily and quickly operated, with little exertion on the part of the user.

A further object of my invention is to provide a device of the type in question that is 20 extremely simple in construction, strong and durable, and highly practical from both the standpoint of the manufacturer and the 25 standpoint of the user; and which, it is believed, may be manufactured at a comparatively low cost.

Various other objects and advantages will become apparent during the continuance of the following description.

These objects are accomplished by such 30 means as are shown in their preferred form in the accompanying drawings, described in the following specification and then more specifically pointed out in the appended claims.

35 In the accompanying drawings wherein like characters designate like parts throughout the several views:

Figure 1 is a view in perspective showing 40 my improved device as in its preferred embodiment;

Fig. 2 is a view in top plan of the culinary article, showing the same equipped with a cleaning brush;

Fig. 3 is a view in perspective of a novel 45 form of cleaning brush and back therefor, that may be employed in connection with my invention;

Fig. 4 is a view in top plan of the device in a slightly modified form;

50 Fig. 5 is a fragmentary view of the side scrapers that are employed in connection with the device as shown in Fig. 4, illustrating more clearly the manner of attaching the same to the base.

55 Before proceeding to a more detailed de-

scription of my invention, it is pointed out that the body structure, as well as the side scrapers and the brush retaining flanges may be made from an integral piece of metal, or other desirable material, to the 60 end that the device is rendered more durable and its longevity added materially to, while its cost of manufacture is reduced to a minimum. However, although this constitutes the preferred embodiment of my invention, 65 it is to be fully understood that I do not limit myself in any definite manner to this construction, since it may be varied materially within the purview of the invention.

In reducing my invention to practice, I 70 first provide a base or body member 10, that is preferably formed of metal, having its longitudinal marginal edges curved and formed into scraping flanges 11 and 12, respectively, extending from the intermediate 75 portion of the body 10 and at an angle thereto. By reason of the curved marginal edges of the scraping flanges, it is obvious that they may be used more expeditiously in connection with the curved sides of circular utensils, since they are more susceptible of conforming with the contour of the 80 respective walls.

On its respective ends, the base 10 is provided with upstanding side portions 13 and 85 14 respectively, that may be formed integral therewith, if it is so desired; the side portion 13 having its longitudinal marginal edges bent to form side scraping flanges 15 and 16, while the longitudinal edges of the other 90 side portions are bent to form suitable brush retaining flanges 17. Scraping flanges 11 and 15 are continuous at their meeting point, that is, the flange 15 is substantially a continuation or lateral projection of the flange 95 11 and vice versa, there being no space, gap or interruption between them. As before stated, the side pieces 13 and 14 may be stamped from a single piece of metal to be integral with the base 10, which is also true 100 of the scraping blades 11 and 12, 15 and 16 and the brush retaining flanges 17. Consequently, it will be noted that the entire body structure of the device may be formed in a solid piece whereby its durability is 105 materially added to while the cost of manufacture of the device, as a whole, is materially decreased.

After the bending of the side portions 13 and 14 into the positions shown in Figs. 1 110

and 2, a handle portion 18 may be interposed therebetween, such as shown, suitable fastening members 19 being employed to attach the ends thereof in a rigid position. 5 This handle may be formed of metal, wood, or any other desirable material, since it forms but an arbitrary feature of the device. However, by reason of its specific disposition, such as shown in Fig. 1, it is 10 apparent that the hand of the operator will be protected at all times, notwithstanding the fact that the device may be freely manipulated to scrape either the side or bottom walls of the respective cooking utensils. 15 Under certain conditions, it has been found expedient to provide the scraping blades 12 with suitably spaced cut outs or notches 20 whereby it may be utilized to dislodge the hardened concretions formed on 20 the walls of the cooking utensils. By the formation of these spaced cut outs or notches, it is apparent that the scraping edge of the respective blade 12 presents a continuously toothed surface that is highly effectual 25 for this particular purpose.

In Fig. 3, I have shown a novel form of brush 21 whose base 22 carries a securing rib 23, that is substantially wedge-shaped when viewed in cross section, for the purpose of reception between the respective retaining flanges 17 of the side piece 14 of the device. The brush may be positioned in place in connection with the device, such as shown in Fig. 2, whereby it may be utilized to brush 30 the foreign particles which have been loosened from the side walls of the cooking utensil through the instrumentality of the scraper blade, and subsequently remove the same therefrom. By using the brush in this capacity, it is believed that a distinct coöperation is resultant, whereby the necessity of employing a separate brush or other device for removing the foreign particles from the utensil, after they have been loosened by the 40 respective scraper blades is eliminated. 45

In Figs. 4 and 5, I have shown my invention as in a slightly modified form, which form will be found very efficient under certain conditions. In this form the base 24 is 50 stamped in the usual manner, however, the longitudinal marginal edges thereof may be cut to extend in parallel relation to each other instead of being curved, as in the form above referred to and subsequently bent to 55 form the scraper blades 25. At one end, the base 24 is provided with an end piece 26 that may be formed integral therewith, such as in the form above referred to, while the latter has its longitudinal marginal edges 60 bent to form the brush retaining flanges 27, similar to the flanges 17 in the other form. At its other end, the base 24 is provided with a second end piece 28 which, as shown in Fig. 5, is bent upon its longitudinal center so that its side portions extend from each

other at a substantially obtuse angle, the marginal edges of the side portions themselves forming the side scraper blades 29, without the necessity of further bending. At its lower end, the piece 28 is provided 70 with a series of stamped ears 30 which are designed to be received through suitable apertures in the base 24, after which they may be bent in the usual manner to securely retain the end piece in position. On the 75 other hand, to add to the rigidity of the side scraper blades 29, the upper marginal edge of the end piece 28 may be overlapped as at 31 (see Fig. 4).

From the foregoing, it is believed that the 80 advantages and novel features of my invention will be readily understood and, therefore, further detail description is deemed unnecessary.

In reducing my invention to practice, I 85 find that both forms thereof as shown herein, are practical and efficient; but realizing that certain conditions will necessarily vary in concurrence with the adoption of my device, I desire to emphasize the fact that 90 various minor changes in the details of construction and in the proportion of parts may be resorted to when required without sacrificing any of the advantages of my invention, as defined in the appended claims. 95

Having thus fully described my invention, what I claim as new and desire to secure by Letters Patent is:—

1. In a culinary article of the character described, a base having scraping flanges, 100 side pieces associated with said base, scraping flanges associated with one of said side pieces, means to attach a cleaning structure to the other of said side pieces, and a handle portion, as and for the purpose specified. 105

2. In a culinary article of the character described, a base having scraping flanges, side pieces associated with said base, scraping flanges on one of said side pieces, means to attach a cleaning structure to the other 110 of said side pieces, and a handle connecting said side pieces by which the device may be operated, as and for the purpose specified.

3. In a culinary article of the character described, a base, scraping flanges on said base, side pieces formed integral with said base to extend therefrom at an angle, scraping flanges on one of said side pieces, retaining flanges on the other of said side pieces, and a handle member associated with 115 said side pieces, as and for the purpose specified.

4. In a culinary article of the character described, a base, scraping flanges formed on the base, and having their outer marginal edges curved, side pieces associated with said base, scraping flanges on one of said side pieces, retaining flanges on the other of said side pieces, and a handle portion connecting said side pieces substantially inter- 125

mediate their ends, as and for the purpose specified.

5. In a culinary article of the character described, a base, said base being oval-shaped when viewed in plan, scraping flanges formed at the longitudinal marginal edges of said base, side pieces extending substantially at right angles from said base, and a handle portion connecting said side pieces, as and for the purpose specified.

6. In a culinary article of the character described, a base, side pieces to be stamped integral with said base, continuous scraping

blades formed on one of the longitudinal 15 marginal edges of said base and one of said side pieces, retaining flanges formed on the other of said side pieces, and a handle connecting said side pieces, as and for the purpose specified.

20 In testimony whereof I affix my signature in presence of two witnesses.

JAMES A. NORDEN.
